UNITED STATES PATENT OFFICE.

GEORGE E. THACKRAY, OF WESTMONT BOROUGH, PENNSYLVANIA.

MOLD-TOP.

1,180,677.

Specification of Letters Patent. Patented Apr. 25, 1916.

Application filed March 23, 1914. Serial No. 826,478.

To all whom it may concern:

Be it known that I, GEORGE E. THACKRAY, a citizen of the United States, residing in the borough of Westmont, in the county of 5 Cambria and State of Pennsylvania, have invented certain new and useful Improvements in Mold-Tops; and I do hereby declare the following to be a full, clear, and exact description of the invention, such as 10 will enable others skilled in the art to which it appertains to make and use the same.

My invention relates to a mold top, one of the adaptations of which is for use on the upper portion of an ingot mold, the ingot 15 mold itself being ordinarily made of metal.

My mold top comprises an outer casing or flask preferably made of metal, open at the top and bottom, and adapted to set on the top of an ingot mold. The inner sides of 20 this flask are provided with a non-conducting refractory lining which may be composed of sand, loam, admixtures of sand and loam, fire-brick or other similar material. The principal essentials of my lining are 25 that it should be much more non-conducting with respect to heat than metal and at the same time sufficiently refractory to reasonably withstand the heat to which it will be subjected by contact with molten metal such 30 as iron, steel or other metals.

My top being in place on an ingot mold, the molten metal is poured into the mold and substantially fills it and the top, and on account of the non-conducting quality 35 of the lining, the molten metal is maintained fluid at, and near the top portion for a period of time very much longer than the other parts of the originally molten metal which are adjacent to, or in contact with, 40 the conducting portions of the metal mold. By means of this arrangement the cavity produced in the ingot or casting, due to shrinkage, is located entirely within the sink-head portion which is contained within 45 my non-conducting top, leaving the other part of the ingot solid and free from shrinkage cavities or pipes. For example, in the manufacture of steel, by reason of the concentration of the shrinkage cavity within 50 the sink-head, I provide an ingot or casting which requires the minimum amount of dis-

card, preparatory to further use in the manufacture of blooms, billets, slabs, bars, structural shapes or other sections.

After an ingot has been cast into a mold 55 provided with my top, the portion adjacent to the non-conducting lining remains fluid for a considerable period of time during which the shrinkage cavity forms therein, the metal which originally was in said cavity feeding downwardly to supply the shrinkage in the other portion of the ingot. Before the metal has entirely set in the interior portion a further quantity of metal may be poured into the preliminary shrinkage cavity to insure that there is sufficient 60 fluid metal to make a solid ingot, although in most cases this is not necessary. After the outer shell of the ingot has been sufficiently set, it may be removed from the mold 65 and allowed to soak or its heat become equalized preferably in a vertical pit furnace.

Having thus given a general description of my invention, I will now, in order to make the matter more clear, refer to the 75 accompanying sheet of drawings forming part of this specification, and in which like characters refer to like parts:

Figure 1 is a transverse sectional elevation of the upper portion of an ingot mold provided with my top, secured in position thereon, as shown, the flask or casing in this case being provided with projections on its inner surface to retain the non-conducting lining, the structure shown in this figure being 80 adapted to set directly on the top of a mold. Fig. 2 is a view similar to Fig. 1, taken on the line II—II of Fig. 3, with the exception that no roughenings are provided on the inner side of the flask or casing, besides 85 which, the non-conducting lining extends downwardly within the mold and its form is maintained by means of anchors or foundry nails embedded therein during its formation. Fig. 3 is a top plan view of the 90 mold top and upper portion of a mold corresponding to Fig. 2. The top plan view of the mold shown in Fig. 3 is the same mold as is shown in section in Figs. 1 and 2, the section shown in Fig. 1 being taken vertically through the axis of the mold and 95 passing through the hold down lugs 3, while 100

the section shown in Fig. 2 is taken on the line II—II of Fig. 3 and passes through the lifting lugs 2. The bottom mold 1 itself shown in all these illustrations is the same, whereas the tops illustrated in Figs. 1 and 2 are slightly different, as the top shown in Fig. 2 has its refractory lining projecting downwardly into the mold and is held by these projections and consequently the metal flask or casing shown in Figs. 2 and 3 is not provided with projecting flanges to coöperate with the hold down lugs 3, as is the case with the top illustrated in Fig. 1, in which latter figure the mold top is secured on the mold by the coöperation of the flanges 6 and the hold down lugs 3 and the horseshoe clamps 7.

Referring now to the characters of reference on the drawings:—1 represents the ingot mold in general, which, in this case, is shown with the large end upward, as this style is preferred in order to produce solid ingots, as compared with a mold, the larger end of which is downward. The lifting lugs of the mold are indicated at 2 in Fig. 2, and similar, but differently shaped, lugs or flanges are indicated at 3 in Fig. 1. The body portion of the ingot is indicated at 4, the flask or casing is indicated generally at 5; the lower flange of the form shown in Fig. 1 is indicated at 6, and in this figure, 7 represent horseshoe clamps adapted to secure the top in position on the mold. The lower inwardly projecting flanges 8 shown on the flask serve to retain the non-conducting material therein. The upper retaining flange or anchor is indicated at 9, while the lifting lugs of the flask or casing are indicated at 10. Gaggers or inwardly extending pins or projections are indicated at 11, which further serve to hold the refractory non-conducting material in position as shown in Fig. 1, whereas no such gaggers are shown in Fig. 2, as in some cases they may be dispensed with. The non-conducting refractory lining is indicated at 12, the shrinkage cavity in the sink-head portion of the ingot or casting is indicated at 13, and as shown in Fig. 2, the anchors for holding the downwardly projecting portions of the lining to the other portions are indicated at 14. The upper or sink-head portion of the ingot is indicated at 15. The lower portion of the non-conducting lining which projects downwardly within and adjacent to the sides of the mold is indicated at 16, while a small space or clearance 17 is provided between same and the sides of the ingot mold in order to insure that the lining can be placed in position despite slight irregularities in it or the mold.

On account of the character of my mold top and the fact that the non-conducting lining can be put into the flask somewhat after the fashion of the ordinary molding

materials and is held securely therein, my mold top may be used over and over again, and in case the inner surface of said lining becomes slightly roughened or broken in use, it can be very easily and cheaply repaired by the application of similar material thereto. 70

I prefer to form the non-conducting lining of dampened material which is rammed in place in manner similar to forming a mold of this character, after which it should be dried to expel most of the moisture and make it hard, although to preserve the non-conducting qualities, it is preferably porous in its body portion. 75

The inside of my lining may be coated with graphite, soap-stone, charcoal or coal-dust, in order to provide a smooth surface. 80

It should be noted that the upper portion of the lining extends over the flange 9 in such a way that when the molten metal is poured into the top, it will not contact with the metal flask or casing. 85

Although I have shown and described my improvements in considerable detail, I do not wish to be limited to the exact and specific details shown and described, but may use such substitutions, modifications or equivalents thereof, as are embraced within the scope of my invention or as pointed out 95 in the claims.

Having thus described my invention, what I claim and desire to secure by Letters Patent is:—

1. A mold top comprising an open flask 100 tapering upwardly and provided with a plurality of inwardly extending projections, a molded non-conducting lining therein, the lower portion of said flask being provided with an outwardly projecting flange, and means for securing the top to the mold by said flange.

2. A mold top comprising a flask open top and bottom, provided with a plurality of inwardly extending projections and outwardly and inwardly projecting flanges on the lower edges thereof, and a molded non-conducting lining applied to its inner sides. 110

3. A mold top comprising a flask open top and bottom, a non-conducting lining applied to its sides and projecting over its upper edges. 115

4. A mold top comprising an open top and bottom flask, adapted to set on top of a mold, inwardly projecting flanges at the upper and lower edges of said flask and a non-conducting lining applied to the inner sides of said flask and extending over the upper edges thereof. 120

5. A mold top comprising a flask of tapering box like structure, open top and bottom, the inner surface being provided with a plurality of flanges extending therefrom, a non-conducting lining within the flask secured thereto by said flanges. 125 130

6. A mold top comprising an open top and bottom flask, flanges projecting inwardly from the upper and lower edges thereof, a non-conducting lining applied to the inner surfaces of said flask and secured therein by said flanges, and means for securing the top on a mold.

In testimony whereof I hereto affix my signature in the presence of two witnesses.

GEORGE E. THACKRAY.
